UNITED STATES PATENT OFFICE.

WILLIAM H. CLARKE, OF BROOKLYN, NEW YORK.

AUTOMATIC FLUID-PRESSURE BRAKE.

SPECIFICATION forming part of Letters Patent No. 693,949, dated February 25, 1902.

Application filed May 24, 1899. Renewed May 21, 1901. Serial No. 61,317. (No model.)

To all whom it may concern:

Be it known that I, WILLIAM H. CLARKE, a citizen of the United States, residing at the city of New York, in the borough of Brooklyn and State of New York, have invented certain new and useful Improvements in Automatic Fluid-Pressure Brakes, of which the following is a full, clear, and exact description.

This invention relates to automatic fluid-pressure railway-brakes. Its object is to furnish an improved form of that part of standard braking apparatus known as the "quick-action triple valve," the function of which in the usual practice of the art is to govern the ingress and egress of fluid-pressure to and from the auxiliary reservoir and brake-cylinder and to cause a quick serial venting of the train-pipe when sudden or emergency applications of the brakes are desired. Such emergency venting of the train-pipe discharges a part of its pressure either into the brake-cylinder or into the atmosphere in the common practice. The quick-acting triple valve herein shown and described is of atmospheric-vent variety, but may be readily adapted without alteration of any of its principal parts to the discharge of fluid-pressure into the brake-cylinder in emergencies.

My invention is fully set forth in the accompanying drawings, in which—

Figure 1 represents a section of the improved valve, a portion of the auxiliary reservoir, and a portion of the pipe leading to the brake-cylinder; and Fig. 2 is a detail of a modification.

The reservoir and cylinder are of well-known construction and need not be described herein.

A is the casing containing that part of the valve commonly known as the "service-valve," said service-valve being indicated by *a* and operated by the piston *a'*, carrying the graduating-valve *a²*. The application and release of brakes in the ordinary or service manner are effected by these parts in the same way as in the well-known Westinghouse triple valve and need not be described at length. The head *a³* carries a flange *a⁴*, upon which the spring *a⁵* impinges, which parts serve to check the movement of piston *a'* at the proper point in service applications of the brakes and to limit its further movement in emergency applications.

a⁶ is a release-port, and *a⁷* is a port in the valve used in emergency applications. 55

B is the casing of the emergency-piston *b*, carrying the stem *b'* and slide-valve *b²* and held in normal position by spring *b³*.

b⁴ is the emergency exhaust-port leading to the atmosphere. The train-pipe connection 60 is made at *b⁵*.

C is the auxiliary reservoir.

c is a port connecting the service-valve casing or chamber A with that portion of chamber B above the emergency-piston *b*. 65

D is the brake-cylinder pipe, and *d* the port connecting it with the service-valve chamber.

All parts are shown in normal position.

In making what is known as a "service application," the train-pipe, valve-chambers, and auxiliary reservoir being charged to normal pressure of, say, seventy pounds per square inch, train-pipe pressure is reduced from five to seven pounds, whereupon the 75 excess pressure to the left of piston *a'* forces it against the head or stop *a³*, unseating graduating-valve *a²* and alining its port with brake-cylinder port *d*. This will permit auxiliary pressure to be expanded into the brake-cylinder in the usual manner until there is a slight preponderance on the right or train-pipe side of service-piston *a'*, when the latter will move slowly to the left until the graduating-valve *a²* is seated, at which point its 85 further motion will be arrested by the resistance of the slide-valve *a*, and pressure will be held in both brake-cylinder and auxiliary reservoir. During these operations ports *a⁶* and *c* are closed by service-valve *a*. Restoration of normal train-pipe pressure forces piston *a'* and valve *a* to normal position, effecting the release of brake-cylinder pressure through ports *d* and *a⁶*. 95

In an emergency application of brakes a sudden reduction of some ten or twelve pounds is made in the train-pipe, which is felt on the under side of piston *b* before piston *a'* is affected by reason of the limitation of the port or passage *b⁷*, leading to the latter, in contradistinction to the unrestricted communication between the train-pipe and the former piston *b*, which is forced down by auxiliary-reservoir pressure acting through port *c*, compressing spring *b³* and opening emergency-valve *b²*. This will be immediately followed 100 105

by a full stroke of piston a' , compressing spring a^5 , opening the large port a^7 at d for quick expansion of auxiliary-reservoir pressure into the brake-cylinder, and closing port c . Auxiliary-reservoir pressure will thus be cut off from the space above emergency-piston b , while upon the full stroke of the latter pressure remaining above the same will be released through leakage-groove b^6 , whereupon spring b^3 will force the emergency piston and valve to normal position.

The closure of emergency-valve b^2 previous to and without any dependence upon the restoration of train-pipe pressure in release of brakes is an important feature of my improved valve, eliminating the liability of failure to effect the release of brakes when desired by reason of the emergency-valve remaining partly open, as in several types of quick-action valve heretofore in use. The absence of packing on the emergency-piston insures the above action of spring b^3 and is a considerable advantage over former similar valves, in which such packing is necessary to prevent leakage of reservoir-pressure while brakes are applied. Also when separate reservoirs or expansion-chambers have been used, as heretofore, to actuate emergency-valves the total fluid-pressure space on each car has been necessarily correspondingly enlarged, resulting in increased pumpwork on the locomotive and other undesirable features, all of which are eliminated by the use of auxiliary-reservoir pressure without opportunity for leakage during either service or emergency application of brakes, as herein described. Further, in quick-action triple valves in general use the emergency piston and valve are actuated directly or indirectly by the service-valve and must therefore await its movements, while in my improved valve the emergency parts are first actuated and are in no wise dependent on the proper operation of the service-valve in applications of brakes, the result naturally being a more speedy and certain transmission of the emergency impulse to the rear of a long train-pipe than can be accomplished by ordinary types of quick-acting triple valves.

By connecting port b^4 and pipe D , as shown in Fig. 2, and limiting the service-piston to its shorter range of stroke it will be readily seen that the improved emergency mechanism herein described may be used equally well in the more common form of quick-acting triple valve, which releases train-pipe pressure to the brake-cylinder in emergency applications of the brakes. This limiting of the service-piston to its shorter or service range of stroke may be accomplished by the means illustrated, consisting of the threaded plug e , which may be screwed in until its head rests against the end of the stem carrying abutment a^8 . Thus when the piston strikes the abutment it is there stopped and port a^7 does not reach port d . In the withdrawn position

the head of plug e acts as a valve to prevent leakage of air.

In trains of fifty cars or more it is highly desirable in emergency applications of brakes to retard the application of the brake-shoes to the wheels of the first fifteen or twenty cars, while offering no opposition to the rapid serial actuation of all the brakes, thus enabling the full pressure of the auxiliary reservoirs to be felt on the brake-pistons of the entire train at practically the same instant. In the present practice the forward brakes are fully applied before the brake-pistons of the rear cars are moved, frequently resulting in severe shocks, pulling out of draw-bars, injury to car-lading, &c. The practically simultaneous application of brakes on long trains at maximum pressure prevents such shocks and enables smooth and exact stops to be made. Hence on long trains fitted with my improved valve the operatives will set the plug e in on a number of cars at the forward end. Then in case of emergency applications the valves on those forward cars will give the full serial venting, but their brakes will not go on until the rear cars have felt the impulse, when all are applied substantially simultaneously.

While I have described and shown a form of quick-action triple valve, using a double stroke of its service-piston in service and emergency applications, respectively, it is evident that where a compound service-piston is used, as in certain forms of such valves well known in the art, the feature of retarding application of forward brakes on long trains, as herein described, may be availed of, and I therefore do not limit myself in this respect to any specific form of triple valve or to any specific means of retarding the flow of auxiliary pressure to the brake-cylinder.

Having thus described my invention, I claim—

1. In a fluid-pressure brake system, the combination with an auxiliary reservoir, and brake-cylinder, of a quick-action train-pipe-discharge valve normally exposed to auxiliary-reservoir pressure on one side and to train-pipe pressure on the other, a service-piston having two lengths of stroke, and means for limiting the movement of said service-piston to its shorter or preliminary traverse in emergency applications of brakes, substantially as described.

2. In a fluid-pressure brake system, the combination of a service-piston having two lengths of stroke with means for limiting the movement of said piston to its first or preliminary traverse, regardless of the amount of reduction of train-pipe pressure, substantially as described.

In witness whereof I subscribe my signature in presence of two witnesses.

WILLIAM H. CLARKE.
